PLAYING CARDS

Application filed January 7, 1928. Serial No. 245,239.

This invention relates in general to improvements in playing cards.

One of the objects of this invention is the provision of a novel form of playing card in which the cards themselves indicate what 5 player, or players, is dealing them.

One of the objects of this invention is the provision of playing card decks provided with indicia to aid in determining who the dealer was and who the next dealer will be. 10

These and other objects as will appear from the disclosure are secured by means of this invention.

This invention resides substantially in the 15 combination, construction, arrangement and relative location of elements all as will more fully appear below.

Referring to the drawings, the single figure is a front elevational view of two decks 20 of cards employing the features of this invention, which decks taken together provide a set.

As is well known in playing the game of bridge it is usual to employ two decks of 25 cards. In this game four persons usually play and they are arranged in two sets of two partners each. The deal progresses around the table from the left and the same partners always deal with the same deck of cards.

Heretofore the only method of keeping the 30 two decks of cards separate and to indicate which set of partners deals them was to provide them on the back with different colored markings, but those who are familiar 35 with the game are well aware of the fact that it is very confusing and difficult to remember after a hand has been played who the dealer is. In keeping the usual score in this game the scorer usually 40 marks the column in which his and his partner's score is kept with the word "We," and the column in which his opponents score is kept is marked "They." It is the purpose of this invention to provide one of the decks of 45 the usual bridge set at the top with the character "We," and the other deck with the character "They." To secure the best results it has been found that it is better to mark each card of each deck with these characters.

50 Thus the scorer and his partner will always deal with the deck marked "We" and their opponents will deal with the deck marked "They."

Referring to the drawings for a better understanding of the invention the figure shows a front elevational view of two decks of cards comprising the individual cards 1 and 2. As is well known in this game two decks provide a bridge set. The cards have been shown in these figures with the back exposed and each card of one deck is provided at the top with the character "They" and each card of the other deck is provided with the character "We." It is, of course, to be understood that the characters "They" and "We" could be placed on the front of the cards or, in fact, at any point on either face of the cards. Furthermore, any other symbol for securing the same result could be used.

In using a bridge set employing the features 70 of this invention the scorer and his partner would employ the deck marked "We", and their opponents would employ the deck marked "They". Thus by means of these cards it is possible for bridge players to 75 always know which deck they deal with and since the question of whose deal it is is most usually raised with respect to the opposing partners it will be possible to always know whose deal it is.

It will be apparent from the foregoing disclosure that I have devised a new and novel form of playing card decks and I do not wish to be limited to the disclosure given for purposes of illustration but rather to the principles of my invention as I have defined them 80 in the appended claims.

What I seek to secure by United States Letters Patent is:

1. As a new article of manufacture a deck 90 of playing cards the backs of which bear a definite determinative indicia designating a definite pair of partners.

2. In combination a deck of cards the backs of which carry indicia definitely designating one pair of players and a second deck 95 of cards, the backs of which bear indicia definitely designating the opponents.

3. In a set of bridge playing cards the combination of two separate decks of cards, 100 used by two sets of partners one deck being marked "We" and one deck being marked "They", such markings always indicating which set of partners will deal each deck.

4. As a new article of manufacture a pair of decks of playing cards, the backs of the cards of one deck bearing the word "We" for definitely indicating the score keeper and his partner in a given game, the remaining deck bearing the word "They" for definitely indicating the opponents of the score keeper and his partner in said game, the several decks being adapted to be assigned to the respective pairs of partners and serving thereafter in ordinary progress of a game to indicate the next dealer.

In testimony whereof I have hereunto set my hand on this 4th day of January, A. D., 1928.
